Des. 844

Garrison Smith, Henry Brown, & Joseph A. Read, of Philadelphia, Pa.

Assignors to

Hayward Bartlett & Co.,

Letters Patent, No. 844, Dated October 7, 1856.

The schedule referred to in these Letters Patent, and making part of the same.

To all whom it may concern,

Be it known that we, Garrison Smith, Henry Brown, and Joseph A. Read, of the City and County of Philadelphia, and State of Pennsylvania, have invented or produced a new and original design for Parlor book stove, and we do hereby declare that the following is a full description of the same, reference being had to the annexed drawing, forming part of this specification, in which:

Figure 1, is a front elevation of the stove.

Figure 2, is a side elevation of the same.

Figure 3, is a rear elevation.

Figure 4, is a plan of top.

Figure 5, is a plan of base plate.

The same letters of reference denote the same part of stove and design.

The front plate A, swells slightly in the middle, and bears the doors B, and C, and the ornament in bas-relief D, beneath the doors C. This ornament is made up of scrolls a, foliage b, and center figure c.

The doors B, are raised by a moulding d, and are each ornamented by a foliage and scrolls in bas-relief. The doors C, have foliage e, surrounding the opening.

This plate, above doors B, has a moulding F, extending also to side plates and having the effect of a cornice. Upon this moulding is the inscription "Patented 1854," in raised capitals and numerals. Between the doors B, and C, is the inscription "Baltimore Parlor Cook" in raised capitals.

The feed swell of the plate is ornamented by the projections f, and foliage g, in bas-relief.

The details of design, configuration, and arrangement of the several ornaments and mouldings of the front plate are as set forth in Fig. 1.

The end plates F, are formed with a swell middle, vertically, and bear in bas-relief foliage h, scrolls i, and figures j, arranged and configured as shown in figure 2.

The back plate G, is embellished with sweeping foliage k, scrolls l, and figures m, entwined, arranged and having the configuration set forth in fig. 3.

The top plate H, has an edge ornamented with foliage n, and upon this plate rests an open work plate I, made up of radial bars o, entwined with scrolls p, and foliage q, having the arrangement and configuration shown in fig. 4.

The base plate J, bears on its edge a wavy ornament r, and in front the pyramidal projections s. It bears the inscription "Hayward Bartlett & Co. Baltimore".

The stone is surmounted by an urn U, ornamented by overhanging pendants t. Its cover is of open work made up of interlaced scrolls u, and figures v, terminating in a handle z, of entwined foliage; the design, configuration, and arrangement of these several parts constituting the urn being as shown in the drawing. The foot F, is ornamented as shown in the drawing.

We claim, as our production, the design, configuration, and arrangement of the ornaments in bas-relief and mouldings, as herein described and shown in the drawings, constituting an ornamental stone design.

Witnessed

Saul L. Clement.
